REMOTE CONTROL GARAGE DOOR
DEMONSTRATION UNIT

John A. Trout, 2761 SW. 4th Court,
Fort Lauderdale, Fla.

Filed Mar. 5, 1965, Ser. No. 84,122

Term of patent 14 years

(Cl. D14—3)

FIG. 1

FIG. 2

FIGURE 1 is a front perspective view of a remote control garage door demonstration unit showing my new design; and

FIGURE 2 is a rear perspective view thereof.

The side not shown is substantially the same in appearance as the side shown.

The dominant features of my design reside in the portions shown in full lines.

I claim:

The ornamental design for a remote control garage door demonstration unit, as shown and described.
